[57] CLAIM

The ornamental design for a golf ball retriever head, as shown and described.

DESCRIPTION

FIG. 1 is a top-right side perspective view of a golf ball retriever showing my new design;

FIG. 2 is a right side elevational view thereof; the undisclosed left side being a mirror image;

FIG. 3 is a top plan view thereof; the undisclosed bottom side is a mirror image of the top shown;

FIG. 4 is a front elevational view thereof; and

FIG. 5 is a rear elevational view thereof.

FIG. 1

FIG. 2

FIG. 3

FIG. 4

FIG. 5
